(57) **CLAIM**

The ornamental design for a combined fishing device with hydrofoil, as shown and described.

DESCRIPTION

FIG. 1 is a bottom plan view of only the hydrofoil of a combined fishing device with hydrofoil, according to my invention;

FIG. 2 is a front elevational view thereof;

FIG. 3 is a view from the right side of FIG. 2;

FIG. 4 is a view from the left side of FIG. 2;

FIG. 5 is a top plan view thereof;

FIG. 6 is a perspective view thereof;

FIG. 7 is a rear elevational view thereof; and

FIG. 8 is a bottom plan view of the combined fishing device with hydrofoil;

FIG. 9 is a front elevational view thereof;

FIG. 10 is a view from the right side of FIG. 9;

FIG. 11 is a view from the left side of FIG. 9;

FIG. 12 is a top plan view thereof;

FIG. 13 is a perspective view thereof; and,

FIG. 14 is a rear elevational view.
